UNITED STATES PATENT OFFICE.

JAMES T. DOUGINE, OF CHICAGO, ILLINOIS.

DOUBLE-TREE.

SPECIFICATION forming part of Letters Patent No. 310,801, dated January 13, 1885.

Application filed April 16, 1884. (No model.)

To all whom it may concern:

Be it known that I, JAMES T. DOUGINE, a citizen of the United States, residing in Chicago, in the county of Cook and State of Illinois, have invented a new and useful Improvement in Double-Trees, of which the following is a specification.

My invention relates to improvements in double-trees; and it consists in connecting the single-trees to the double-tree at each end thereof by means of springs for the purpose of relieving the horse's shoulders against sudden jerks or shocks.

My invention also consists in making the clevis, clip, or attachment to the double-tree integral with or rigidly connected to one of the stems or pull-rods of a coil compression-spring, so that the pull-rod cannot turn or swivel on the clevis, the other pull-rod, which is attached to the single-tree, being arranged not to turn or swivel on the former, whereby the single-tree hook is held with its point in a vertical position in order to prevent casual disengagement of the single-tree.

It also consists in providing the pull-rod, which is attached to the double-tree, with an eye for the stay-chain hook.

In the accompanying drawings, which form a part of this specification, and in which similar letters of reference indicate like parts, Figure 1 is a plan view of a double-tree embodying my invention. Fig. 2 is an enlarged detail plan view of the spring-connection, and Fig. 3 is a central longitudinal section of the same.

In the drawings, A represents a tongue, B a double-tree, C the single-trees, and D springs connecting the double-tree to the single-trees. These springs are preferably coil compression-springs. One of the pull-rods, d, is provided with a hook, d', to engage with the staple or eye c of the single-tree, and is secured at its other end by screw-threads to the cap or plate d'', which fits against the end of the spring. The other pull-rod or draw-bar, d'', is made in two branches, which fit inside the spring and astride the rod d, each of said branches being secured by suitable nuts, d', or otherwise to the

cap or plate d'', which bears against the opposite end of the spring. The pull-rod d' is provided at its end with a socket, clip, or attachment, d'', by which it is secured to the end of the double-tree. This clip or attachment d'' is preferably made in the form of an open-ended socket adapted to surround or embrace the end of the double-tree, the open end of the socket thus permitting the sides of the same to be clamped down tight upon the double-tree. The cap or plate d'' is provided with openings for the two branches of the draw-bar d'', and said cap slides on the same as a guide, while the cap d'', having a central opening, slides on the draw bar or rod d. The branches of the rod d'' also prevent the cap d'' from swiveling or turning, so that the hook d' of the rod d may be kept turned up, and thus prevent the single-tree from becoming disengaged with said hook.

I am aware that traces have heretofore been provided with springs, as well as that the double-tree has been secured to the tongue by a spring-connection, and I disclaim such devices as forming no part of my invention. d' is the eye for the stay-chain E.

What I claim is—

1. The combination of double-tree B with single-tree C, coil compression-spring D, caps d' and d'', and pull-rods d and d'', said pull-rod d being provided with a hook for attachment to the single-tree, and said pull-rod d' having two branches sliding in said cap d'', and being provided with open-end socket d'', for attachment to the double-tree, substantially as specified.

2. The combination of double-tree B with single-tree C, coil compression-spring D, cap d'', pull-rod d', provided with two branches secured to said cap, and having clip d'' secured to the double-tree and stay-chain eye d', cap d'', and pull-rod d, provided with hook d' for the single-tree, substantially as specified.

JAMES T. DOUGINE.
